UNITED STATES PATENT OFFICE

OTTO H. HARTMANN, OF KASSEL-WILHELMSHOHE, AND WILHELM JUNG, OF KASSEL, GERMANY, ASSIGNEES TO SCHMIDT'SCHE HEISSDAMPF-GESELLSCHAFT, M. B. H., OF KASSEL-WILHELMSHOHE, GERMANY, A CORPORATION OF GERMANY

LOCOMOTIVE BOILER

Application filed February 9, 1928, Serial No. 253,140, and in Germany February 14, 1927.

The present invention relates to locomotive boilers, and is an improvement on the boiler shown in U. S. Patent No. 1,648,396 issued November 8, 1927, to Otto H. Hartmann. In said patent, a locomotive boiler is shown which comprises a longitudinal low-pressure boiler, and a high-pressure boiler supplied with heat from a water-tube fire box. Between the fire box and the longitudinal boiler is provided a combustion channel defined by water-tubes which communicate with the high-pressure section, that is to say, with the water-tube fire-box.

In order to increase the generation of high-pressure steam and to make it possible to vary the production of high-pressure steam so as to obtain any desired ratio between it and the low-pressure steam, and thus to make the most favourable use of all the advantages from the use of high-pressure steam, the present invention provides, in addition to the water-tubes surrounding and defining the combustion channel, additional water-tubes located in the combustion channel and communicating with the high pressure water-tube fire-box. These additional water-tubes are provided in any desired number, and are preferably arranged in groups extending transversely of the combustion channel, and provided at their upper and lower ends with collecting chambers, which may communicate with the high-pressure drum or, in case of indirect high-pressure steam generation, with a heat-exchange element disposed in said drum.

The accompanying drawing illustrates one form of the invention as applied to a two-stage locomotive boiler.

Fig. 1 is a fragmentary longitudinal section through the water-tube fire box and a part of the longitudinal boiler;

Fig. 2 is a section taken on the line 2—2 of Fig. 1; and

Fig. 3 is a section on the line 3—3 of Fig. 1. The drawing shows the invention applied to a boiler wherein the high-pressure steam is generated indirectly, but it will be understood that the invention is equally applicable to a boiler arranged for the direct generation of high-pressure steam.

The drawing shows a locomotive boiler arranged to generate low-pressure steam in a longitudinal fire-tube boiler 5, and high-pressure steam in a high-pressure drum 3. The numeral 1 represents the longitudinal water chambers surrounding the grate, and 2 indicates transverse chambers connected with chambers 1. Water-tubes 4 extend upwardly from chambers 1 to form a fire box, the tubes crossing each other below the high-pressure drum 3, of which there may be one or more.

The upper ends of tubes 4 are connected to a pair of headers 10, every alternate tube being bent transversely to connect with the header 10 on the opposite side of the boiler, while the remaining tubes extend substantially vertically to the header on the same side of the boiler as the base of the tubes. The tubes at each side of the fire box are arranged in two rows in such a manner that the tubes 4 of the inner row serve as risers for the water heated by the combustion gases, and the tubes 4^a of the outer row serve to conduct the cooler water downwardly. Water-tubes 7 are disposed between the fire box and the longitudinal boiler 5, and define a combustion channel, the floor of the channel being formed by water-tubes 8, 8^a. Tubes 7 are connected at their lower ends to chambers 9 and at their upper ends to the headers 10 of the circulating system, alternate tubes being connected to opposite headers as in the case of the fire-box tubes. Tubes 7 are also arranged in two rows on each side of the combustion channel, so that the inner row of tubes 7 conducts the water upwardly while the outer row of tubes 7^a conducts the cooler water downwardly. Tubes 8^a have their forward ends connected to a transverse chamber 13, and their rear ends to a transverse chamber 12. Chamber 13 communicates through risers 14 with headers 10, from which tubes 14^a extend downwardly to the chamber 12. Tubes 8 connect with transverse chambers 11 and 2 at their forward and rear ends respectively. Risers 11^a extend from the transverse chamber 11 to the headers 10, the return movement of the heating medium taking place through the tubes 4^a to the longitudinal chambers 1 and 2.

Fig. 2 is a section taken on the line 2—2 of Fig. 1; and

Fig. 3 is a section on the line 3—3 of Fig. 1. The drawing shows the invention applied to a boiler wherein the high-pressure steam is generated indirectly, but it will be understood that the invention is equally applicable to a boiler arranged for the direct generation of high-pressure steam.

to the front transverse chamber 2 connected thereto.

In addition to the water-tubes surrounding the combustion channel, additional groups of water-tubes are provided (in the present case five groups) consisting of parallel water-tubes 17 extending transversely of the combustion channel. The tubes 17 of each group lie in a common plane extending transversely to the axis of the channel, and are secured at their upper and lower ends to the transverse chambers 19 and 18 respectively, the upper chambers 19 being directly connected to the headers 10, and the lower chambers to descending tubes 20, as shown at the left of Fig. 2.

The steam generated by the heating medium in all the water-tubes of the fire box and of the combustion channel is collected in headers 10, which give up their heat to the drum 3 by means of heat-exchange elements such as the heating coils 15 lying in the drum. The condensate formed in coils 15 returns through tubes 16 to the lower water chambers, from which a new cycle of circulation begins.

As will be evident from the drawings, the additional water-tubes 17 greatly increase the heating surface provided in the combustion channel, and consequently increase the generation of high-pressure steam, so that the output of the locomotive due to the high-pressure steam is increased and the coal consumption accordingly decreased.

While we have shown five groups of water-tubes 17, this number may of course be made smaller or greater as found desirable, depending on the desired ratio between high-pressure steam and low-pressure steam.

In the combustion channel, tubes 17 are so arranged as to leave a central passage 21 through which the rear tube sheet of the longitudinal boiler can be inspected and repaired. The space 21 is normally closed by a member 22 of fireproof material which prevents the passage of the combustion gases through the passage 21 and which deflects them laterally through the tubes 17. Member 22 is mounted so as to be easily removable to allow access to the tube sheet of the longitudinal boiler 5 when desired.

Tubes 17 may be formed in various ways, for instance in the form of coils, and they may also be directly connected to headers 10 if desired.

Various modifications may be made without departing from the nature of the invention as set forth in the appended claims.

We claim:

1. A locomotive boiler comprising a water-tube fire box, upper and lower longitudinal headers to which the tubes in said fire box are connected, a high pressure steam drum, coils in said drum communicating with the headers and with the tubes comprising the

fire box, a fire-tube boiler in which low pressure steam is generated by combustion gases from said fire box, water tubes connected to the aforesaid headers forming a constricted combustion channel located between said fire box and said fire-tube boiler, and a plurality of additional tubes traversing said combustion channel, said additional tubes communicating with transverse chambers which are connected to the aforesaid headers whereby a complete circulation through the additional tubes in the combustion channel and the coils in the aforementioned drum is effected.

2. A locomotive comprising a water-tube fire box, a drum connected to the upper ends of the tubes of said fire box to form therewith a high-pressure steam boiler, a fire-tube boiler in which low pressure steam is generated by the combustion gases from said fire box, water-tubes forming a constricted combustion channel located between said fire box and said fire-tube boiler, the tubes of said combustion channel being connected to said drum to transfer heat from the combustion channel to said drum, a plurality of additional tubes transversing said combustion channel and communicating with the high-pressure water-tube fire-box to increase the ratio of high pressure steam generated to that generated in the low pressure boiler, said additional tubes being arranged to provide a passage extending from the fire-box to the rear tube sheet of the fire-tube boiler, and a removable member normally closing said passage to prevent the combustion gases from passing therethrough.

In testimony whereof we have hereunto set our hands.

OTTO H. HARTMANN.
WILHELM JUNG.
